UNITED STATES PATENT OFFICE.

GIANNI BETTINI, OF NEW YORK, N. Y.

DESIGN FOR A PHONOGRAPH-FRAME.

SPECIFICATION forming part of Design No. 26,701, dated March 2, 1897.

Application filed January 23, 1897. Serial No. 620,473. Term of patent 14 years.

To all whom it may concern:

Be it known that I, GIANNI BETTINI, of the city, county, and State of New York, have invented and produced a new and original 5 Design for Phonograph-Frames, of which the following is a specification, reference being had to the drawings accompanying and forming a part thereof.

Figure 1 is a plan view of a phonograph-frame, showing my design; and Fig. 2 is an elevation view.

The feature of the design consists in a phonograph-frame made in the conventional representation of a lyre.

15 Referring to the drawings, A represents the frame, which is made in the shape of a

lyre and is provided with standards, as a' a^2 a^3 a^4 , for supporting the phonograph mechanism.

B represents a transverse bar joining the two arms of the lyre, and b' b^2 b^3 represent the strings of the lyre.

What I claim is—

The design for a phonograph-frame, substantially as shown and described. 25

In testimony whereof I have signed my name to this specification in the presence of two subscribing witnesses.

GIANNI BETTINI.
